[57] CLAIM

The ornamental design for a rotatable merchandise display unit, as shown and described.

DESCRIPTION

FIG. 1 is a top, front, and right side perspective view of a rotatable merchandise display unit showing my new design;

FIG. 2 is a left side elevational view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a top, front, and left side perspective view of an alternate embodiment thereof;

FIG. 8 is a right side elevational view of the embodiment of FIG. 7;

FIG. 9 is a front elevational view of the embodiment of FIG. 7;

FIG. 10 is a rear elevational view of the embodiment of FIG. 7;

FIG. 11 is a top plan view of the embodiment of FIG. 7; and,

FIG. 12 is a bottom plan view of the embodiment of FIG. 7.

The partial aperture pattern is understood to repeat uniformly over the surface of the pegboard portions.
